HOUSING FOR A STEAM GENERATING APPLIANCE

Norman A. Steinkamp, Chicago Heights, and Bernard B. Bluestein, Des Plaines, Ill., assignors to Sunbeam Corporation, Chicago, Ill.

Filed Mar. 19, 1973, Ser. No. 342,817

Term of patent 14 years

Int. Cl. D15—05

U.S. Cl. D7—164

FIG. 1 is a perspective view of a housing for a steam generating appliance embodying our new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a sectional view taken along line 6—6 of FIG. 3.

We claim:

The ornamental design for a housing for a steam generating appliance, as shown.
